(57) **CLAIM**

The ornamental design for a beverage cooler, as shown and described.

DESCRIPTION

The present design relates to a cooler for use in storing beverages of various kinds, including beer, where the overall proportions of the cooler are compatible with the receipt of a full case of the select beverage.

FIG. 1 is a front elevational view of the beverage cooler of the present invention.

FIG. 2 is a rear view of the beverage cooler as depicted in FIG. 1.

FIG. 3 is a left side view of the beverage cooler as depicted in FIG. 1.

FIG. 4 is a top view of the beverage cooler as depicted in FIG. 1.

FIG. 5 is a bottom view of the beverage cooler as depicted in FIG. 1; and,

FIG. 6 is an isometric view of the beverage cooler as depicted in FIG. 1.

The broken lines are for illustrative purposes only and form no part of the claimed design.
